UNITED STATES PATENT OFFICE.

AAGE E. WINCKLER, OF RACINE, WISCONSIN, ASSIGNOR OF ONE-HALF TO J. I. CASE
THRESHING MACHINE COMPANY, OF RACINE, WISCONSIN, A CORPORATION.

EXPLOSIVE-ENGINE.

1,287,550.

Specification of Letters Patent. Patented Dec. 10, 1918.

Application filed May 5, 1916. Serial No. 95,669.

To all whom it may concern:

Be it known that I, AAGE E. WINCKLER, a subject of the King of Denmark, and a resident of Racine, county of Racine, and 5 State of Wisconsin, have invented certain new and useful Improvements in Explosive-Engines, of which the following is a description.

The invention relates to internal combustion or explosive engines and more particularly to explosive engines of the revolving cylinder type, designed for aeronautic purposes such as set forth in my prior Patent 10 No. 1,174,459, dated March 7, 1916.

15 The objects of the present invention are to provide an improved construction of this type of explosive engine, to improve the valve mechanism, to provide improved cooling means and improved means for lubricating the moving parts.

20 The invention consists in the features of improvement hereinafter set forth, illustrated in the preferred form in the accompanying drawings and more particularly 25 pointed out in the appended claims.

Figure 1 is a partial end view of the improved engine with the crank casing cover removed and with parts shown in section. Fig. 1^a is a detail section of parts shown in 30 Fig. 1. Fig. 2 is a side view of the improved engine with all of the cylinders but one removed and such cylinder shown in end elevation. Fig. 3 is a plan view of the engine cylinder shown in Fig. 2.

35 As in the construction set forth in the prior patent referred to, the engine has a stationary crank shaft, a crank casing carrying a series of cylinders, which rotate in the form shown, and which are radial with respect to the crank shaft in the present 40 construction. The cylinders are provided with pistons coupled by connecting rods to the stationary crank shaft.

45 The rotatable crank casing comprises a heavy annular casting 1 whereon the engine cylinders are mounted, a section 2 and heads 4 or cap plates 3 and 4. The heads 3 and 4 are provided with hub portions which are journalled in suitable bearings on a frame 50 work 5. The head 3 is bolted to the end of the casing section 2 and in the form shown is provided with an extension 6 whereon a propeller is mounted when the engine is used as an aeronautic motor. The annular 55 casing section 1 is provided with a series of

circular openings 7 for receiving the cylinders 8. The casing section 2 and the head 4 are provided with flanges 9 and 10 which abut against the edges of the annular portion 1 and are secured thereto by bolts 11 60 which extend through the annular portion 1 between the openings 7 therein.

The cylinders 8 are preferably formed of cast steel and the walls thereof are relatively thin. The cylinders fit snugly within 65 the openings 7 of the annular portion 1 and the inner portions of these openings are enlarged to form seats for locking rings 12 (see Fig. 1) which fit within annular grooves formed in the outer surface of each cylinder 70 8 adjacent its inner end. The rings 12 are split and are formed of spring steel. In assembling the parts, the inner end of each cylinder is passed through one of the openings 7 so that its projects beyond the inner 75 face of the wall of the annular portion 1. The spring ring 12 is then placed in position thereon and the cylinder drawn outwardly until the ring engages the seat formed at the inner portion of the openings 7. In the 80 preferred construction shown, the fastening bolts 11 overlap the rings 12 so that these parts and the cylinders are securely held in position. At the same time, any one of the cylinders may be readily removed 85 for repairs or the like.

Each cylinder is provided with a series of integral ribs which are arranged close together and which extend spirally about the cylinder from the inner to the outer ends 90 thereof. Preferably, also, these ribs increase in height from the inner to the outer end of the cylinder. When the engine is in operation the spiral ribs on the revolving cylinders force the adjacent air outwardly 95 so that a strong current of air passes continually from the inner to the outer end of the cylinders and through the grooves between the ribs and thereby effectively cools the cylinders. The fact that the cylinder 100 walls are quite thin also aids in preventing the overheating. The longitudinal spiral ribs also serve to strengthen the cylinder walls so that they can be quite thin and light.

Beyond the outer ends of the ribs 13 the wall of each cylinder is thickened and provided with an external screw thread and a flanged head 14 is threaded thereon. Each head is provided with an outwardly project- 110

ing portion 15 which is provided with inlet and exhaust chambers 16 and 17, each of the inlet chambers 16 being connected to a radial supply pipe 18 (see Fig. 3) and each of the 5 exhaust chambers being connected to an elbow shaped exhaust pipe 19. The exhaust pipes as shown in Fig. 1 extend outwardly so that the passage of the exhaust there-through will aid in forcing air currents outwardly and in radial direction over the engine cylinders.

The cap 4 of the crank case is hollow and forms an inlet manifold which is connected to the outer end of each cylinder by one of the radial pipes 18. A suitable carbureter 20 mounted on the frame communicates with a pipe 21, which extends axially within the head 4. The chambers 16 and 17 in each cylinder head are provided at their inner ends with seats for inlet and exhaust valves 22 and 23. The stems 22' and 23' of these valves extend outwardly through suitable stuffing boxes, an outer portion of each valve stem is provided with an annular groove 25 which is arranged to be engaged with the forked end of a leaf spring 24. These springs between their ends rest upon supporting lugs 25 that are fixed respectively to the adjacent ends of the supply and exhaust 30 pipes 18 and 19. The outer end of each spring is provided with two openings which are engaged by the hook shaped outer end of a bolt 26. These bolts are adjustably threaded into lugs formed upon the adjacent 35 portions of the pipes 18 and 19 and are provided with lock nuts 26'.

The springs hold the valves in closed position and the latter are arranged to be opened by a pair of levers 27 and 28 which 40 are connected by pivot studs 29 to lugs 30 and 31 formed upon the cylinder head. The lever 27 is pivoted between its ends and is provided with a roller 27' at one end which is arranged to engage the stem 22' of the admission valve and the opposite end of the lever is connected to a valve actuating rod 32. The exhaust operating lever 28 is pivoted at its outer end and its inner end is arranged to engage the stem 23' of the exhaust 50 valve. This lever is engaged and actuated by a stud 33 adjustably threaded through a split lug 34 on the adjacent portion of the lever 27 and held in adjusted position by a clamp screw 35. The parts are so arranged 55 that an outward movement of the valve actuating rod 32 will open the inlet valve and an inward movement thereof will open the exhaust valve.

The valve actuating rods 32 extend inwardly through openings 36 formed in the portion 2 of the crank case and are actuated by a gear driven cam therein. The portions 1 and 2 of the crank case are filled with oil to lubricate the moving parts. To prevent 65 leaking around the valve actuating rods 32,

flexible coupling sleeves 37 of rubber or the like are connected to the crank case and to the rods. The outer end of each flexible sleeve extends over a flanged collar 38 (see Fig. 1), on the valve rod and is gripped between the flange thereof and a nut threaded on the reduced portion of the collar. A pin 40 extends through the nut and collar and fixes the same in place upon the valve rod. The inner end of each flexible sleeve 37 is 75 fastened in liquid tight fashion by a wire 41 within the groove of a collar 42. This collar is formed upon the outer end of a bushing 43 which surrounds the rod 40 and is threaded through a collar 44 and into one 80 of the openings 36 of the crank casing section 2. The opening in the bushing 43 is considerably larger than the rod and this construction permits of the proper movement of the rod and at the same time provides a liquid tight joint between the same 85 and the crank case.

A series of pipes 45 are connected to the casing section 2 adjacent the inner ends of the actuating rods and each of these pipes 90 is connected by a coupling 46 to a pipe 47. The latter is provided with branches 47' that lead respectively to the bearings formed in the lugs 30 and 31 for the pivot pins 29. When the engine is in operation, the oil in 95 the crank casing is forced outwardly by centrifugal action through the pipes 45 and 47 and thus keeps the bearings for the valve actuating levers 27 and 28 properly lubricated.

In Fig. 1 the cap plate 3 is removed to show the parts within the part 2 of the crank case. This part is provided with a web 48 and a central hub 49 that is journaled upon the end portion 50 of the stationary crank shaft, a series of levers 51 being mounted therein upon pivot studs 52 that are fixed to the web 48. Each of these levers is provided at one end with a roller 53 and at its opposite end with a stud 54 100 that extends through a transverse opening in the enlarged inner end of one of the valve actuating rods 32. An abutment 55 threaded into the enlarged portion of the valve rod engages the stud 54. The rollers 110 53 are engaged by a cam 56 that is rotatably mounted upon the hub portion 49. Springs 57 coiled about the valve actuating rods 32 and within the flexible coupling pieces 37 are interposed between the collars 38 and 42. 120 These springs hold the rollers 53 snugly in engagement with the cam 56 and take up all lost motion in the valve operating parts.

The cam 56 is provided with high portions *a* for opening the exhaust valves, low 125 portions *b* for opening the inlet valves and intermediate portions *c* for holding the valves closed during the compression and working strokes. In the form shown there are four sets of these portions about the 130

periphery of the cam and seven cylinders and hence the cam is driven relatively to the rotating crank case in a seven to eight ratio to properly effect the four-cycle operation of the engine cylinders.

The hub 49 of the casing section 2 is provided with a projecting sleeve 49' which surrounds the end portion 50 of the stationary crank. The hub of the cam 56 is 10 rotatably mounted upon this sleeve as most clearly shown in Fig. 1^a and is provided at its outer end with a gear 57 which is integral therewith or suitably attached thereto. A driving gear 58 is keyed upon the 15 outer end of the sleeve 49' so that it rotates with the gear casing and this driving gear is connected to the cam gear 57 by two pairs of intermediate idler gears 59 and 60, each pair of idler gears being connected to rotate 20 together. The idler gears are rotatably mounted upon the ends of a spider 61 which has two diametrically opposed arms and a central hub that is keyed in position upon the end portion 50 of the stationary crank 25 shaft. A cap plate 62 fixed to the reduced outer end portion of the crank shaft overlaps the hub of the spider and holds it in position.

As above stated, the gearing is proportioned to drive the cam relatively to the 30 rotating crank casing in a seven to eight ratio.

In operation, the idler gears 59 and 60 are connected to rotate together but, in the 35 construction shown, they are adjustably connected. Each gear 59 is provided with an enlarged hub 59' which is rotatably mounted within an enlarged bearing in the outer end of one of the arms 61. The gear 60 is 40 fixed to the end of a short axial shaft 63 which extends through the hub of the gear 59. A cap plate 64 fits over the end of the shaft 63 and overlaps the outer end of the spider arm to hold the gears in position 45 thereon. This plate and the two gears 59 and 60 are provided with a series of openings 65 arranged to receive fastening bolts 66 by which the two gears are connected. The distance between the bolt holes in the 50 gear 60 is slightly different than the distance between the bolt holes in the gear 59 so that by taking out the bolts the two gears may be adjusted to a slight extent relatively to one another and then reconnected, this 55 adjustment being less than the distance between two adjacent gearing teeth. In this way the valve operating cam 56 can be nicely adjusted relatively to the rotating crank case to thereby time the operation of the 60 valves as desired.

Each cylinder head is provided with a socket for receiving a spark plug 67. These plugs are connected by conductors 68 to a

distributer ring 69 on the rotating crank case. A magneto 70 furnishes current to a 65 brush carried by a holder 71 and coöperating with the distributer ring 69.

It is obvious that numerous changes may be made in the details set forth without departure from the essentials of the invention, 70 as defined in the claims.

I claim as my invention:

1. In a rotary explosive engine, the combination of a rotary crank case adapted to contain lubricating oil, a series of substantially radial cylinders, valves mounted on the outer ends of said cylinders, valve actuating rods projecting from said crank case, actuating devices on said crank case including a series of rocking levers connected to 80 the inner ends of said rods, and flexible coupling sleeves connected to said rods and to said crank case.

2. In a rotary explosive engine, the combination of a rotary crank case adapted to 85 contain lubricating oil, a series of substantially radial cylinders, valves mounted on the outer ends of said cylinders, valve-actuating arms pivotally mounted on the outer ends of said cylinders, rods connected to said 90 arms and extending into said crank case, actuating devices with said case for said rods, means forming liquid-tight joints between said case and said rods, and pipes extending from said case and connected at 95 their outer ends to the bearings of said pivoted valve actuating arms.

3. In a rotary explosive engine, the combination of a rotary crank case, a series of substantially radial cylinders mounted 100 thereon, a fixed crank shaft in said case, inlet and exhaust valves mounted on the outer ends of said cylinders, valve operating rods, a cam in said crank case concentric with the axis of said shaft for actuating said rods, 105 a gear fixed to said cam, a main drive gear, and a pair of adjustably connected intermediate gears meshing respectively with said main drive gear and the gear fixed to said cam.

4. In a rotary explosive engine, the combination of a rotary crank case, a series of substantially radial cylinders mounted thereon, a fixed crank shaft in said case, 115 valves on the outer ends of said cylinders, valve operating rods projecting into said crank case, rock arms in said case connected to the inner ends of said rods, a cam for actuating said arms, gears fixed respectively to said cam and to said crank case, a pair of 120 adjustably connected idler gears meshing with said first mentioned gears, and a support for said idler gears mounted upon said crank shaft.

AAGE E. WINCKLER.
